The ornamental design for a computer terminal for manufacturing data acquisition, as shown and described.

DESCRIPTION

FIG. 1 is a right side, front and top perspective view of one embodiment of the computer terminal for manufacturing data acquisition showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.
